(57) **CLAIM**

The ornamental design for connector for fluid supply for patient infusion, as shown and described.

DESCRIPTION

FIG. 1 is a top, front, right side perspective view of a connector for fluid supply for patient infusion, according to a first embodiment;

FIG. 2 is a bottom, rear, left side perspective view of a connector for fluid supply for patient infusion, according to a first embodiment;

FIG. 3 is a front elevational view of a connector for fluid supply for patient infusion, according to a first embodiment;

FIG. 4 is a top, front, right side perspective view of a connector for fluid supply for patient infusion, according to a second embodiment;

FIG. 5 is a bottom, rear, left side perspective view of a connector for fluid supply for patient infusion, according to a second embodiment; and,

FIG. 6 is a front elevational view of a connector for fluid supply for patient infusion, according to a second embodiment.

The broken lines in the drawing views are included for the purposes of illustrating the environment of the connector for fluid supply for patient infusion while in use that forms no part of the claimed design and portions of the connector for fluid supply for patient infusion that form no part of the claimed design. Any portion of the drawings shown in broken lines forms no part of the claimed design.

1 Claim, 4 Drawing Sheets
